FAN CONSTRUCTION

Edward E. Mix, Los Angeles, Calif.; Gail E. Mix,
executor of said Edward E. Mix, deceased

Application September 1, 1950, Serial No. 182,757

2 Claims. (Cl. 170—173)

1

This invention has to do with a fan construction and it is particularly concerned with a fan involving a spider of improved formation or construction. It is a general object of the present invention to provide a simple, practical, effective, structure that is light and inexpensive and which is strong, durable and rigid.

It is common and in many instances commercially desirable to form fans primarily of sheet metal, and this type of fan is commonly formed with a hub, a spider on the hub and blades on the arms of the spider. When a sheet metal spider is employed the entire fan construction may be more or less flexible and not as rigid as desired, in that the sheet metal arms of the spider are subject to flexure.

It is a general object of the present invention to provide a fan construction employing a sheet metal blade-carrying spider, which spider is so formed as to be light, strong, and rigid.

Another object of the invention is to provide a fan spider of the general character referred to which is such that it can be easily and accurately manufactured without resort to special manufacturing operations or processes.

A further object of the present invention is to provide a stiff, light, strong fan spider which can be attached to a hub through conventional construction and which may have blades attached to its arms in any desired manner.

The fan construction provided by the present invention involves a hub which may be of conventional formation, a spider carried by the hub, and blades carried by the spider. The hub is preferably a simple, elongate member with a central shaft receiving opening, and it may have a reduced end portion concentric with the shaft opening and receiving the center of the spider. When this construction is employed a flange is formed on the outer end of the reduced part of the hub to retain the spider on the hub. The spider is preferably of simple construction or formation and may be formed entirely of a single body of sheet metal so that it has a center portion carried by the hub and arms radiating from the center portion. The center portion of the spider is preferably a flat plate-like body with a central opening that receives the reduced part of the hub. The arms that project from the center portion are preferably radially disposed and are suitably spaced around the axis of the structure. In a typical case each arm has a shank portion that adjoins the center portion and projects radially therefrom and has a head which is in the nature of an enlargement on the

5 outer end of the shank portion provided to carry a blade. The blades carried by the arms may vary in form or design as circumstances require, and they may be fastened to the heads of the arms in any suitable manner, as by riveting or the like. In accordance with the present invention the sheet metal spider hereinabove referred to is so formed or shaped that it may be advantageously made of a thin body of sheet metal with the heads of the arms pitched or angularly related to support the blades in the desired manner. In accordance with the invention a central stiffener is provided in the form of an annular rib on the central portion of the spider, concentric with the axis of the fan, which rib can be advantageously pressed or formed in the sheet metal in the course of performing other operations on the spider. Further, in accordance with the present invention the various edges or edge portions of the spider not covered or occupied by blades, are deflected somewhat from the general plane of the spider or from the plane of the spider portions adjacent the edges. The deflected or turned edge portions which, in a typical case, extend along the edges of the arms and heads, and along the curved parts that connect the edges of the arms, serve to materially stiffen and reinforce the entire spider so that the spider supports the blades from the hub without undesirable flexibility. By providing the turned edge portions at opposite edges of the blade where it attaches to the head, the blade is efficiently braced and held in position on the head.

35 The various objects and features of my invention will be fully understood from the following detailed description of a typical preferred form and application of the invention, throughout which description reference is made to the accompanying drawings, in which:

40 Fig. 1 is an end or face view of a fan embodying the present invention. Fig. 2 is an edge or side view of the fan, being a view taken as indicated by line 2—2 on Fig. 1. Fig. 3 is an enlarged detailed sectional view taken as indicated by line 3—3 on Fig. 1, and Fig. 4 is a detailed transverse sectional view taken as indicated by line 4—4 on Fig. 3.

45 The fan construction as illustrated in the drawings involves, generally, a hub A, a spider B, and blades C connected to the spider by fastening means E.

50 The hub A illustrated in the drawings is of simple form, being an elongate block round in cross section and provided with a central longitudinal shaft opening 10. The hub is provided with a

set screw 11 that serves to retain the hub on the shaft when it is applied thereto.

The spider B is applied to or carried by the hub A and in turn supports the blades C. In any particular case the specific formation of the spider may be varied, depending upon the nature of the blades or the number of blades. In a typical case, as is shown in the drawings, there are three equally spaced blades C, in which case the spider B is formed with a central portion 15 which is applied to the hub A and with arms having shanks 16 that project from the portion 15 and have enlargements or heads 17 at their outer ends to carry the blades. The spider in its preferred form is a single or unitary body of sheet metal and the central portion of the spider is a flat plate-like part suitably joined to the hub A, for instance, to one end thereof. In the case illustrated the hub has a reduced spider receiving part or neck 18 at one end and the portion 15 of the spider has an opening 19 into which the hub neck 18 is entered. A flange 20 formed on the outer end of neck 18 overlies the portion 15 of the spider to retain the spider on the end of the hub.

In the preferred form of the invention the shanks 16 of the spider arms are equally spaced around the central part 15 and project radially therefrom, the several shanks being alike and of substantially uniform width from the point where they join the portion 15 to the points where the heads 17 occur. The heads 17 provided on or projecting from the outer ends of the shanks 16 are like and in the case illustrated each is in the nature of an enlargement on the outer end of the shank conforming in general shape to the inner end or base portion 20 of blade C. The shanks 16 of the spider arms, and possibly all or portions of the heads 17, are twisted or pitched relative to a plane or planes normal to the longitudinal axis of the structure so that the blades C are supported in the desired manner to give them a suitable pitch. In a typical situation the heads 17 may be flat to receive flat base portions of the blades, in which case the entire pitch is gained by shaping or twisting the shanks between the points where they join the central portion 15 and where the heads 17 connect to them.

The fastening means E is provided for securing the base portions 20 of the blades to the heads 17 may vary widely. In the case illustrated a plurality of simple rivets 25 are shown securing each base portion 20 to its supporting head 17 and in the particular case illustrated each base portion has an inwardly projecting extension 20 that overlies a part of the shank that carries the blade supporting head and a rivet joins this extension to the said shank.

The present invention provides a construction or formation which serves to effectively strengthen and lend rigidity to the spider, as above described, to the end that the spider may be made of light sheet metal and yet have maximum strength and rigidity. In the preferred form of the invention the central portion 15 of the spider is materially strengthened and is made rigid by providing an annular rib 30 on the portion 15 concentric with the axis of the fan. In the case illustrated the rib is pressed or stamped into the central portion 15 so that it provides an indentation at one side of the portion 15 and a boss-like hump at the opposite side. In addition to the central embossed rib 30 the spider is stiffened and reinforced by turned edge portions 35 that occur at the several exposed edges

of the sheet out of which the spider is formed and make the shanks and heads substantially concavo-convex in cross sectional configuration. In the particular case illustrated there are opposite edge portions 35 at either side of each shank 16 and head 17 of the spider and these side edge portions are joined by curved edge portions 35a that connect the side edge portions where the side edge portions adjoin the central portion 15. The edge portions 35 and 35a are turned or deflected to extend at an angle relative to the plane or planes of the spider parts from which the edge portions project, and in the particular case illustrated the edge portions are bent or deflected along lines 40 that parallel the extreme edges of the spider and are spaced inwardly a suitable distance therefrom. In the preferred form of the invention the turned or deflected edge portions of the spider are continuous and uniform, as shown throughout the drawings, and they terminate at the outer ends of the heads. Where the shanks 16 are twisted or pitched to give the desired angle to the blades C as shown throughout the drawings the turned or deflected edge portions of the spider continue and follow the contour of the shanks, to the end that the shanks are effectively reinforced and stiffened.

From the foregoing description it will be apparent that the combined stiffening rib 30 and turned edge portions 35 and 35a serve to materially stiffen and reinforce the entire spider without adding any parts or excessive weight thereto. Furthermore, it is important to observe that these features can, in practice, be incorporated 35 in the spider construction in the course of its manufacture without requiring special operations such as might otherwise complicate manufacture. The reinforcements that I have provided can be provided or incorporated in the spider in the 40 course of flanking or forming operations such as are required to form a sheet metal spider with a central portion and projecting arms.

Having described only a typical preferred form and application of my invention, I do not wish to be limited or restricted to the specific details 45 herein set forth, but wish to reserve to myself any variations or modifications that may appear to those skilled in the art and fall within the scope of the following claims.

Having described my invention, I claim:

1. A fan including, a rigid hub, a sheet metal spider carried by the hub and having a substantially flat center portion fixed to the hub, substantially flat circumferentially spaced shanks 55 radiating from the center portion and heads on the outer ends of the shanks and projecting beyond the edges thereof, and like separate blades attached to and projecting from the heads, the center portion of the spider having an annular stiffening rib projecting from one side thereof and the shanks having substantially flat middle portions and substantially flat edge portions in planes inclined relative to the planes of the middle portions, the edge portions at adjacent edges of adjoining shanks being joined together.

2. A fan including, a rigid tubular hub, a sheet metal spider carried by the hub and having a substantially flat center portion fixed to the hub, circumferentially spaced shanks radiating from the center portion and substantially flat heads on the outer ends of the shanks and projecting therefrom, and like separate blades attached to and projecting from the heads, the center portion of the spider having an annular stiffening 75 rib concentric therewith and projecting from one

side thereof and the shanks having substantially flat middle portions and substantially flat edge portions in planes inclined relative to the planes of the middle portions, the edge portions at adjacent edges of adjoining shanks being joined together, the blades having extensions overlapping and attached to the shanks and confined between the edge portions thereof and each of the heads having edge portions projecting from one side thereof and the blade carried by the head being attached to that side thereof and being guided by and between the said edge portions thereof.
